MACHINE FOR SEALING WAXED
PAPER BAGS

Arthur B. McLaughlan, Salem, Oreg.

Application May 18, 1942, Serial No. 443,431

2 Claims. (Cl. 226—56)

This invention relates in general to devices for sealing the open ends of bags containing food products, or other materials, where the sealing is to be accomplished by means of heat and pressure.

More specifically, this invention relates to machines for sealing waxed paper bags containing food products, such as fresh berries and the like, which are subjected to "quick freezing" or "sharp freezing," such freezing of the products for their preservation taking place immediately after the bags have been completely sealed; and this invention relates in particular to the customary packaging of frozen fruits or other foods in which a waxed paper bag is placed as a liner in an open carton, then filled with a food product and sealed, after which the carton is closed and the entire package then subjected to the freezing process and kept in a freezing temperature.

A number of devices and machines have been invented for heat-sealing waxed paper bags used for such packages, but most of these are more or less complicated and are expensive to build and to maintain.

An object of this invention is to provide an improved sealing machine which will be comparatively simple in construction and require a minimum amount of upkeep.

Another object of this invention is to provide a pressure heat-sealing machine which is adjustable for packages of slightly different size.

One difficulty encountered in most sealing devices for waxed paper bags is that when extra thicknesses of the waxed paper attempt to pass between the heat-pressing elements—for example, when extra folds have been inadvertently made in the open bag ends to be sealed—the extra thicknesses of the waxed paper clog and jam between the heat-pressing elements, damaging the package in question and temporarily delaying further functioning of the device. An important object of my present invention, accordingly, is to avoid this difficulty by providing heating-pressing elements of rollers which will be automatically adjusted to accommodate extra thicknesses of paper without interfering with their normal operation. This latter object I accomplish by employing heated rollers for the pressing elements and by having one of the rollers adjustably spring-mounted.

Another problem encountered when heating-pressing elements are employed for sealing such bags is involved in maintaining just the right amount of pressure, inasmuch as too great a pres-

sure, especially if grooved sealing rollers are used, might damage or tear the waxed paper, while too little pressure might not produce a perfect seal. A further object of this invention is to provide adjusting means whereby the sealing pressure may be modified as required and maintained at constant predetermined, but adjustable, amount at all other times.

It is also desirable that the packages or cartons should be marked at the time of sealing to indicate the lot or operator's number, so that should any package later be found to be imperfectly sealed it can be traced for the purpose of ascertaining the probable cause of the imperfect sealing. A still further object therefore is to provide suitable means for marking the package or carton at the time of sealing.

These and other objects I accomplish by making my sealing machine in the manner hereinafter briefly described with reference to the accompanying drawings.

In the drawings:

Fig. 1 is a side elevation of my improved machine with a waxed paper bag and its carton container shown in broken lines;

Fig. 2 is a front elevation of the same machine; Fig. 3 is a fragmentary plan view of the forward end of the machine, with portions broken away for the sake of clarity and with a portion shown in plan section, the figure corresponding to the line 3—3 of Fig. 2; and

Figs. 4A and 4B are fragmentary views of the meshing gears connected to the heating pressing rollers, illustrating respectively the positions of the gears when ordinary and when extra thicknesses of waxed paper are being sealed.

The machine includes a pair of horizontal plates comprising bottom plate 10 and top plate 11 which are adjustably secured in parallel spaced relation by a plurality of vertical rods 12. These rods preferably have both ends threaded, as shown at Figs. 1 and 2, and pairs of clamping nuts 12' are mounted on the threaded ends of the rods so as to enable the rods and plates to form a rigid but adjustable machine frame.

A pair of parallel guides 13 are supported on the bottom plate 10 and extend longitudinally through the machine for the purpose of guiding the cartons 17 containing the paper bags to be sealed.

These guides 13 are adjustably secured to the bottom plate 10 by screws or bolts 13' (Fig. 3) extending through slots 15 in plate 10 and thus enable the guides 13 to be placed further apart or closer together to accommodate larger or smaller cartons. A conveyor belt 16, mounted on suit-

able rollers (not shown) and driven in any suitable manner, conveys the filled cartons through the machine from left to right as viewed in Fig. 1. The forward ends of the guides 13 are flared outwardly as shown at 14 in Fig. 3 to facilitate the proper positioning of the cartons on the conveyor belt.

As the cartons 17, with the filled waxed paper bags 18 therein, pass through the machine, the open ends of the bags pass between two heated rollers 19 and 20 (Fig. 2) mounted on vertical axes and supported from the top plate 11. The roller 19 is attached to a shaft 21 which is supported for rotation in a hub 23 secured to plate 11 extending above and below the plate 11 as shown in Fig. 2. The shaft 21 is extended downwardly below roller 19 and passes through a suitable opening in the bottom plate 10 and is connected at its lower end to suitable driving means (not shown) by which rotation is imparted to the shaft 21 and roller 19. A gear 24 is attached to the shaft 21 above the hub 23.

The other heat-pressing roller 20 is secured at the bottom end of a shaft 26 which is rotatably supported in a U-shaped bracket 27 extending through a suitable slotted opening in the top plate 11.

This U-shaped bracket 27 has a pair of horizontal arms 28, one located above and one below the plate 11, which are mounted on a stub shaft 29 supported in a hub 30. Thus the U-shaped bracket 27, and therewith the shaft 26, are movable in a horizontal arc, thereby permitting the position of the roller 20 to be varied with respect to the roller 19, the axis of the roller 19 being fixed. A gear 25 is attached to the shaft 26 above the U-shaped bracket 27 in such position as to mesh with the gear 24 on the shaft 21.

In order to hold the roller 20 normally in a desired position with respect to the companion roller 19, I provide adjustable means at opposite sides of the bracket 27 as shown in Figs. 3 and 2. This means includes a stop screw 34, adjustably positioned in a lug 35, the purpose of which is to determine the minimum spacing between the rollers 19 and 20; and, at the opposite side of the bracket 27, a spring 31 is mounted between the bracket 27 and an adjustable screw 32, the purpose of which spring is to hold the bracket, normally against the stop screw 34 but to permit slight movement of the bracket away from the stop screw 34 under special conditions. The adjustable screw 32 is mounted in a lug 33 attached to the plate 11 and the tension of spring 31 may be adjusted by the adjustment of screw 32.

I have found that, in sealing waxed paper bags, especially when fluted or serrated rollers are used, it is best to provide a slight spacing between the rollers corresponding approximately to, but not exceeding, the thickness of two sheets of the waxed paper. Thus it will be noted in Fig. 2 that the rollers 19 and 20 are spaced apart approximately the thickness of the bag end 18 to be sealed, that is, the thickness of two sheets of the waxed paper. This spacing is of course adjustable by means of the stop screw 34. In the event that extra thicknesses of the waxed paper, due to any extra folds in the waxed paper bag or to any other causes, are forced between the heat-pressing rollers 19 and 20, the spring 31 will automatically permit the spacing between the rollers to be sufficiently increased to compensate for the extra thickness of the waxed paper, thus preventing any clogging or jamming of the paper between the rollers, and the adjusting screw 32

can be set so as to provide just the right amount of spring pressure desired for such extra thicknesses of the waxed paper. Even under unusual circumstances, however, the variation of the paper thickness will be relatively so small that the gears 24 and 25 (Figs. 2 and 4) will continue to remain in mesh even though the spacing between the heat-pressing rollers is temporarily increased.

The shafts 21 and 26, to which the rollers 19 and 20 are attached, are hollowed out to permit heating elements to be inserted for the purpose of heating the pressing rollers. Electrical heating elements 36 are placed in the hollowed shafts and are connected respectively to pairs of ring conductors 37 mounted at the top of each shaft. Wiper contact arms 38, secured to a binding post 39, conduct electrical current, obtained from a suitable source, to the heating elements in the usual manner.

Before sealing the tops of the waxed paper bags, it is desirable to exhaust most of the air from the filled bags, and this is very simply done in my machine by pressing down slightly on the bags on both sides of the flattened wall surfaces which are to be sealed. For this purpose I provide a pair of pressing guides 40 extending longitudinally into the machine at the forward end. The forward ends of these guides 40 are flared outwardly and upwardly, as shown in Figs. 2 and 3. I have found it also desirable to have these guides 40 inclined transversely slightly from the horizontal, as shown in Fig. 2, to conform more to the natural slope of the contents in the bags at the top. Furthermore, these guides are also adjustably mounted and are supported from the top plate 11 by rods 42 which have threaded ends for the adjustable clamping nuts 42'. This adjustable feature enables cartons and bags of slightly different sizes to be used in the machine. These guides 40 not only exhaust most of the air from the tops of the bags before the sealing, but also aid in guiding and positioning the flaps or tops of the side walls of the waxed paper bags for the pressing-heating-sealing operation performed by the rollers 19 and 20.

The cartons or containers 17, in which the bags are placed before being filled, have customary lids 46 which are folded over in the usual manner after the sealing of the bags has been completed. While the bags are being sealed in the machine, the carton lids must be kept out of contact with the heated sealing rollers, and for this purpose, and also for the purpose of placing identification marking on the carton lids, I provide two pairs of horizontal lid guides 43 and 44, the upper pair 43 being adjustably supported from the top plate 11 and the lower pair 44 being adjustably supported by the bottom plate 10. Both of these pairs of carton lid guides are secured to rods 45 which have their opposite ends threaded to accommodate the adjustable clamping nuts by which they are attached to the upper and lower plates of the machine frame. These pairs of guides thus hold the carton lid in horizontal position removed from the heat-pressing rollers while the sealing of the bags is taking place, and guide the carton lids to an identification stamping means which is provided at the rear of the machine.

The stamping of the carton lids is performed by a stamping assembly including a base member 47 (Fig. 1) on which are mounted removable indicia 48 for the purpose of placing any desired identifying marking on the cartons, such as the

packer's number, etc. Since cartons in which frozen foods and other similar products are packaged generally have a waxed coating, the base member 47 is heated in order that heat may be conducted to the marking indicia 48 to enable the identification marking to penetrate the waxed surface of the carton lid. This heating is obtained through the medium of an electric heating element 51 placed in the base member 47 and connected to a suitable source of electric current. As the lid 46 of a carton passes over the heated indicia 48, a plunger plate 49, attached to the bottom of a plunger rod 50, presses the carton lid down against the heated indicia 48 for a slight instant. The plunger rod 50 is actuated by a pivoted offset arm 52. The opposite or forward end of the offset arm is arranged to be engaged by cam segments 55 located on the top face of the gear 24. A spring 56 normally retains the plunger rod 50, and therewith the rear end of the offset arm 52, in raised position, and holds the forward end of the offset arm 52 against the top surface and cam elements of the rotating gear 24. The offset arm 52 is pivotally mounted in a pair of supports 54 by means of a shaft 53. Should no marking of the carton be desired, the base member 47 and the plunger rod 50 can be removed from the machine.

I claim:

1. A machine for heat-sealing waxed paper bags including a pair of top and bottom plates, a pair of heating pressing rollers mounted on vertical shafts and located below said top plate, the shaft for one of said rollers supported in a bearing on said top plate, the shaft for the other roller supported in a hinged bracket pivotally mounted on said top plate and adapted to swing in a horizontal plane, means for positioning said bracket and second mentioned shaft whereby to control the spacing between said rollers, said latter mentioned means including a positive, adjustable stop for maintaining a predetermined minimum spacing between said rollers and a resilient element normally holding said bracket against said stop but allowing said minimum spacing to be temporarily increased to accommodate extra thicknesses of waxed paper passing between said rollers, means for heating said rollers, means for rotating said rollers, a pair of longitudinally extending pressing guides located below said rollers, and extending forwardly and rear-

wardly thereof, said guides acting to bring the top flaps of each bag into position in preparation for the heat sealing and to cause air to be exhausted from said bags by pressing down on said bags prior to and during the sealing, said guides supported from said top plate, conveying means supported on said bottom plate for conveying said bags through said pressing guides and pressing rollers, and means for adjusting the position of said top plate with respect to said bottom plate, whereby bags of different size can be accommodated in said machine merely by adjusting the position of said top plate with respect to said bottom plate.

2. A machine for heat-sealing waxed paper bags comprising a pair of top and bottom plates, a pair of heating pressing rollers mounted on vertical shafts and located below said top plate, the shaft for one of said rollers supported in a fixed bearing on said top plate, the shaft for the other roller supported in a hinged U-shaped bracket pivotally mounted on said top plate and adapted to swing in a horizontal plane, means for positioning said bracket and second mentioned shaft whereby to control the spacing between said rollers, said latter mentioned means including a positive, adjustable stop for maintaining a predetermined minimum spacing between said rollers and an adjustable spring normally holding said bracket against said stop but allowing said minimum spacing to be temporarily increased to accommodate extra thicknesses of waxed paper passing between said rollers, means for heating said rollers, means for rotating said rollers, a pair of longitudinally extending pressing guides located below said rollers, and extending forwardly and rearwardly thereof, said guides acting to bring the top flaps of each bag into position in preparation for the heat sealing and to cause air to be exhausted from said bags by pressing down on said bags prior to and during the sealing, said guides adjustably supported from said top plate, conveying means supported on said bottom plate for conveying said bags through said pressing guides and pressing rollers, and means for adjusting the position of said top plate with respect to said bottom plate, whereby bags of different size can be accommodated in said machine merely by adjusting the position of said top plate with respect to said bottom plate.

ARTHUR B. MC LAUCHLAN.
